CABINET MIRROR UNIT

Harley H. Miller, Middletown, Ohio, assignor to
 The Philip Carey Manufacturing Company, a
 corporation of Ohio

Application March 7, 1936, Serial No. 67,700

8 Claims. (Cl. 88—100)

This invention relates to cabinets and particularly to wall and medicine cabinets which are adapted to be positioned in a convenient place on some part of the wall and provided with a closure having a mirror mounted thereon. Cabinets are standard equipment in bathrooms for medicine cabinets and for shaving mirrors, same usually being mounted on the wall below one or between two lighting fixtures.

10 The conventional construction comprises a cabinet having any number of shelves therein and provided with a door hinged to one side wall. A mirror is mounted on the door, and there may also be provided a stop means which limits the opening of the door. The stop means is not always used but is preferable inasmuch as the cabinets are usually positioned on a wall with a light on either side and some means is usually desired to prevent the door from swinging back and hitting that light which is on the side towards which the door swings when opened. These cabinets are more or less standard in form, being ordinarily square or rectangular with the door and mirror conforming to the same configuration 25 as the cabinet and usually of the same size.

It is the aim of the present invention to provide a cabinet unit having a mirror more artistic in design, independent of the configuration of the cabinet and associated with the cabinet so that 30 it can be opened or moved in a predescribed path away from the cabinet, moving at first substantially parallel to the wall until just before the mirror is opened to its extreme position when it will then be tilted with the mirror positioned to 35 one side of one of the lights, thereby being in a position for more convenient use. In this movement the mirror is also moved away from the opposite light which is behind the mirror when same is open to extreme position. This may be 40 carried out by mounting the mirror or mirror and door upon a double pivoted bracket and having a double pivoted guide and stop to describe the movement of the mirror on one pivot in relation to the movement of the bracket on the other 45 pivot. The guide and stop is disposed to form a support for one edge of the mirror when same is opened to extreme position.

For a better understanding of the invention, reference may be made to the accompanying drawing in which:

Fig. 1 is a plan view of a wall section having mounted thereon a cabinet and mirror unit embodying the present invention;

Fig. 2 is a view partly in cross-section looking down from lines 2—2 in Fig. 1;

Fig. 3 is a view partly in cross-section, the same as in Fig. 2, but with the mirror open to extreme position; and

Fig. 4 is a detailed cross-sectional view of the hinge structure.

Referring to the drawing in which like numerals are used to designate like parts, numeral 1 designates a portion of a wall recessed to receive a cabinet 2 of any conventional construction. It is usually rectangular in shape and provided with any number of shelves or divisions therein. The cabinet may be formed of any suitable material but is usually of metal painted or enameled with a decorative coating of any desirable color. These units are generally conventional fixtures for bath rooms, and are commonly positioned on the wall adjacent one or between two light fixtures 3. Heretofore, the doors for the cabinet and the mirrors mounted thereon have conformed to the configuration of the cabinet and been hinged to one side wall with the result that the mirror is in position for use only when the door is closed. It swings away and out of position when the door is opened. One aim of the invention, among others, is to have the mirror in convenient position for use both when the door is opened and closed or in any intermediate position. The mirror 4 is fixed to the door or backing 5 by any suitable means such as clips 6 attached to the door and projecting to engage the marginal edge of the mirror and secure it in position. The door and mirror are mounted upon a bracket 7, that is advantageously substantially U-shaped in construction with an intermediate portion 8 fitting into a recess or eye 9 of a clip 10, fixed to the door or backing and with trunnions 11 on the legs 12 fitting into the recesses or eyes 13 of clips 14 on the cabinet. This bracket connection typifies any suitable means for hinging the door or mirror to the cabinet for the purpose of providing a double pivot between the cabinet and the door. This arrangement permits the entire mirror and door to move outwardly from the wall for a distance equal to the extent of the legs of the bracket device, with the bracket pivotally connected to the cabinet and also to the door. The clip may preferably be formed from a single strap of material about one inch wide bent at approximately right angles with the intervening eye portion and end portions 14a and 14b. One end 14a contacts with the inside face of the side wall and the other end 14b projects to contact the underside of the facing piece 14c.

Cooperating with the mirror and cabinet is a

guide device 15 in order to cause the mirror and door to move in predescribed path upon the bracket as the bracket is pivoted. One end of the guide device is pivoted at 15a to the cabinet 5 by a clip 16, and the opposite end is pivoted at 17 to the door by a clip 18. The clip 16 which is attached to the cabinet is preferably located on a medial line between the side walls of the cabinet and the length of the guide is slightly less 10 than one half of the width of the cabinet and about two thirds of the length of the bracket legs. Accordingly when the mirror is open to extreme position, the bracket will be at about right angles with the wall and the guide will be 15 at about a forty-five degree angle or more. Clip 16 is preferably spaced a distance from the margin of the mirror and will serve more or less as a back rest together with the bracket when the door is open. Also in this position the mirror is 20 advantageously placed for reflection from the light when one is standing before it.

From the above description it will be apparent that the door upon first being opened moves away from the cabinet and more or less parallel with 25 the face of the wall, until just before reaching its extreme open position, when it will then be tilted at about a forty-five degree angle or more with the wall. This results in having the mirror at all times facing directly to one standing in 30 front of it. There is, because of the guide, no possibility of it swinging against either of the lights and the guide further permits adjustment to any angular position from closed to extreme open position.

35 While the invention has been described in detail in reference to one preferred embodiment, it will be understood that it is not so limited but that there may be various changes without departing from the spirit of the invention.

40 I claim:

1. In combination with a wall cabinet adapted to be mounted on a wall, a mirror of greater transverse dimension than the cabinet covering one side of the cabinet, a bracket having an intermediate portion pivotally connected to the mirror and terminal portions pivotally connected to the cabinet, and guide means pivoted fixedly to the cabinet and to the mirror at different respective points than those at which the bracket and its intermediate portion are pivotally connected to said mirror and cabinet, cooperating with the bracket to prevent free swinging of the mirror.

2. In combination with a wall cabinet adapted 55 to be mounted on a wall, a mirror of greater transverse dimension than the cabinet covering one side of the cabinet, a bracket pivotally connected with the mirror intermediately of its side edges and with the side wall of the cabinet, and 60 a guide pivoted intermediately of the side walls of the cabinet and also intermediately of the side edges of the mirror, but at a point different from that at which the bracket is hinged to the mirror, said guide being less in length than the 65 bracket to cause tilting of the mirror at an angle to the cabinet.

3. In combination with a wall cabinet of substantially rectangular configuration, a substantially circular mirror having a diameter as great 70 as the diagonal of the cabinet, a hinge means for mounting the mirror to serve as a closure for the cabinet, and a guide means hinged fixedly to the mirror, at a different point than that at which the mirror is connected to the hinge, and 75 to the cabinet for causing said mirror to move

in a path upon the hinge described by the guide means.

4. In combination with a substantially rectangular cabinet adapted to be mounted on a wall, a mirror of greater transverse dimension than 5 the cabinet for covering one side of the cabinet and hinged thereto by a bracket, a portion of the bracket fixedly pivoted to the mirror and another portion of the bracket fixedly pivoted adjacent a side wall of the cabinet, and means pivotally connected at one end to the mirror, at a point different from that at which the bracket is hinged to the mirror, and at the other end to the cabinet intermediate the sides thereof, all so arranged and the bracket and the means 15 between their respective pivots being unequal in length that access to the cabinet is obtained by moving the door outward and toward the side of the cabinet.

5. In combination with a substantially rectangular cabinet adapted to be mounted on a wall, a substantially circular mirror having a diameter as great as the diagonal of the cabinet of greater transverse dimension than the cabinet adapted to be swung out and away from the cabinet, a 25 bracket having a portion pivotally connected to the cabinet and an opposite portion pivotally connected to the mirror, and a link of lesser length than the bracket having one end pivotally connected to the cabinet intermediate the sides 30 thereof and the other end pivotally connected to the mirror, at a point different from that at which the bracket is hinged to the mirror, said bracket and link being pivotally connected to the mirror intermediate the top and bottom 35 thereof.

6. In combination with a substantially rectangular cabinet adapted to be mounted on a wall having top and bottom walls surrounding a recessed portion, a substantially circular mirror 40 of greater transverse dimension than the cabinet forming a closure for the recessed portion, said mirror hinged by a suitable bracket to the cabinet for opening and closing same, a portion of the bracket fixedly pivoted to the mirror and another portion of the bracket fixedly pivoted adjacent a side wall of the cabinet, and a link 45 pivotally connected at one end to the mirror, at a point different from that at which the bracket is hinged to the mirror, and at the other 50 end to the cabinet, all so arranged to cause the mirror when being opened to move initially outward from the cabinet and towards one side wall in a plane substantially parallel with the front of the cabinet and then on further movement 55 to assume an angle to the front of the cabinet.

7. In combination with a substantially rectangular cabinet adapted to be mounted on a wall having top and bottom walls surrounding a recessed portion, a substantially circular mirror 60 of greater transverse dimension than the cabinet forming a closure for the recessed portion, said mirror hinged by a suitable bracket to the cabinet for opening and closing same, a portion of the bracket fixedly pivoted to the mirror and another portion of the bracket fixedly pivoted 65 adjacent a side wall of the cabinet, and a link pivotally connected at one end to the mirror, at a point different from that at which the bracket is hinged to the mirror, and at the other 70 end to the cabinet, all so arranged to provide a mirror which irrespective of its position is outside of the recessed portion and to cause the mirror when being opened to move initially outward from the cabinet and towards one side wall 75

in a plane substantially parallel with the front of the cabinet and then on further movement to assume an angle to the front of the cabinet.

8. In combination with a substantially rectangular cabinet adapted to be mounted on a wall having top and bottom side walls surrounding a recessed portion, a substantially circular closure having a diameter as great as the diagonal of the cabinet of greater transverse dimension than the cabinet for the recessed portion hinged by a suitable bracket to the cabinet for opening and closing same, a portion of the bracket fixedly pivoted to the closure and another portion of the

bracket fixedly pivoted adjacent a side wall of the cabinet, and a link pivotedly connected at one end to the closure and at the other end to the cabinet, all so arranged to support the closure, at a point different from that at which the bracket is hinged to the mirror, outside of the recessed portion of the cabinet and to cause the closure when opened to move initially outward from the cabinet and towards one side wall in a plane substantially parallel with the front of the cabinet and then on further movement to assume an angle to the front of the cabinet. ⁵ ¹⁰
